DESIGN FOR A PIPING

A. Waldo Rockwood, Winchester, Mass., assignor
to Haley-Cate-Rockwood Co., Inc., Everett,
Mass., a corporation of Massachusetts

Application November 18, 1933, Serial No. 49,787

Term of patent 14 years

To all whom it may concern:

Be it known that I, A. WALDO ROCKWOOD, a citizen of the United States, and a resident of Winchester, county of Middlesex and State of Massachusetts, have invented a new, original, and ornamental Design for Piping, of which the following is a specification, reference being had to the accompanying drawing, forming part thereof.

The drawing of my piping, showing edge stitching, preferably of contrasting colors with the piping strip, wherein

Fig. 1 is a perspective view on an enlarged scale, and

Fig. 2 is an end view of my piping.

I claim:

The ornamental design for piping, as shown and described.

In witness whereof, I hereunto subscribe my name this day of October 4, 1933.

A. WALDO ROCKWOOD.
